(57) **CLAIM**

The ornamental design for a separable drinkware and object holder as shown and described.

DESCRIPTION

FIG. 1 is a first perspective view showing the separable drinkware and object holder in a separated configuration.

FIG. 2 is a second perspective view showing the separable drinkware and object holder of FIG. 1 in a connected configuration.

FIG. 3 is a first side view of the separable drinkware and object holder of FIG. 1 in a separated configuration.

FIG. 4 is a first side view of the separable drinkware and object holder of FIG. 1 in a connected configuration.

FIG. 5 is a second side view of the separable drinkware and object holder of FIG. 1 in a separated configuration.

FIG. 6 is a second side view of the separable drinkware and object holder of FIG. 1 in a connected configuration.

FIG. 7 is a third side view of the separable drinkware and object holder of FIG. 1 in a separated configuration.

FIG. 8 is a third side view of the separable drinkware and object holder of FIG. 1 in a connected configuration.

FIG. 9 is a fourth side view of the separable drinkware and object holder of FIG. 1 in a separated configuration.

FIG. 10 is a fourth side view of the separable drinkware and object holder of FIG. 1 in a connected configuration.

FIG. 11 is a top view of the separable drinkware and object holder of FIG. 1; and,

(Continued)

FIG. 12 is an underside view of the separable drinkware and object holder of FIG. 1.
